CLAIM

The ornamental design for an anti-theft device for attachment between an automobile steering wheel and brake pedal, as shown and described.

DESCRIPTION

FIG. 1 is a top, front, and left side exploded perspective view of an anti-theft device for attachment to an automobile steering wheel and brake pedal showing my new design; FIG. 2 is a front elevational view thereof, the rear being a mirror image of that shown;

FIG. 3 is a left side elevational view thereof;

FIG. 4 is a right side elevational view thereof;

FIG. 5 is a top plan view thereof; and,

FIG. 6 is a bottom plan view thereof.
